UNITED STATES PATENT OFFICE.

FREDERICK H. MILLER, OF WILKINSBURG, PENNSYLVANIA, ASSIGNOR TO WESTINGHOUSE ELECTRIC & MANUFACTURING COMPANY, A CORPORATION OF PENNSYLVANIA.

INSULATOR.

Application filed January 8, 1921. Serial No. 435,809.

My invention relates to insulators and particularly to insulators of the pin type.

The object of my invention is to provide a device of the above indicated character that shall be adapted for outdoor or other service where conducting matter, such as rain, sleet or dust, is likely to accumulate thereon and that shall, under such conditions, utilize the insulating value of air to substantially a maximum degree of efficiency.

Heretofore, it has been usual to provide insulators of the pin type having a single insulating member or a plurality of such members, on one or more of which petticoat portions are formed to function as rain sheds and to provide proper creepage distances. Also, as set forth in Patent No. 1,129,520, issued to the Westinghouse Electric & Manufacturing Company on an application filed by Karl C. Randall, Sydney W. Farnsworth and Chas. Le G. Fortescue and in Patent No. 1,374,998, by Chas. Le G. Fortescue and George I. Gilchrest, and assigned to the Westinghouse Electric & Manufacturing Company, it has been usual to provide insulators of the pin type having equipotential surfaces and surfaces conforming to the electrostatic flow lines in a dielectric field.

As set forth in the above mentioned patents, when the sides of an insulator, extending between two zones or conductors of different potential, lie parallel to the electrostatic field, substantially the insulating value of air is obtained, and an obstruction in the field or an irregularity on the surface of the insulator will cause the concentration of dielectric stresses and thus, a breakdown of the field.

However, for outdoor or other service when conducting particles, such as rain, sleet and dust, are likely to impinge against the insulating surfaces, it has been found necessary to provide petticoats or other similar means to maintain the surfaces dry and to give proper creepage distances under all conditions. Such petticoats, if disposed at random or in a haphazard manner, constitute obstructions to the dielectric field which, as above mentioned, cause the field to break down at voltages much below those which

are sustained by an insulator having the petticoats properly formed and positioned.

Proper forming and positioning of the insulator petticoats is fully set forth in the above mentioned Patent No. 1,374,998 and consists principally in the forming of the petticoats to have surfaces at right angles to the field. This construction prevents the concentration of the field stresses at any particular points on the insulator and provides substantially the same dielectric strength as air, with the exception of the slight change in the specific inductive capacity of the space between the positions of different potential in which the petticoats are disposed.

One other exception to the principle that petticoats having equi-potential surfaces do not disturb the dielectric field, as set forth in the above-mentioned Patent No. 1,374,998, is that there will be a tendency for the dielectric stresses to concentrate at the extreme edges of the petticoats. This tendency is overcome by extending the petticoats to positions in the field where the latter is relatively weak, so as to render the tendency of the stresses to concentrate a negligible factor for the particular field in which the insulator is located.

In practicing my invention, I provide an insulator that may entirely, or for a greater portion of its length, utilize the dielectric strength of air in the manner set forth in the patent above mentioned. This is accomplished by eliminating all or a certain number of the petticoats to permit the main body surfaces to lie, unobstructed, in parallel relation to the field. To protect the body surfaces from the accumulation of conducting particles, such as rain or dust, and to compensate for the loss in creepage-surface distance caused by the elimination of the petticoats, I provide an insulating shell or cover-member of substantially bowl shape that conforms to the dielectric field and surrounds the insulator in spaced relation thereto.

In the accompanying drawings, Figures 1 and 2 are similar views, partially in section and partially in elevation, of different forms of my invention.

As shown in both figures, an insulator structure 1 comprises a plurality of superposed nested insulating members 2, 3 and 4, a pin 5 and an outer insulating cover or embracing member 6.

The upper member 2 is provided, in a usual manner, with a groove 7 for the reception of a conductor 8 and with a peripheral groove 9 for the reception of a tie wire 10.

10 The member 6 may be secured in position in any suitable manner, but is, preferably, provided with a vertically projecting tubular portion 13 that may be cemented in position in the lower end of the member 4.

15 This construction permits the insulator and the member 6 to be assembled and handled as a unit. An aperture, or apertures, 14 may be provided at the bottom of the member 6 to serve as drainage means for such water of condensation as may collect therein.

As explained in the above mentioned Patent No. 1,874,998, the pin 5 may be of metal, or of insulating material covered by metal, or the inner surface of the lower insulating member may be coated with metal so as, in co-operation with the tie wire 10, to cause the dielectric field to assume a predetermined substantially bowl shape, similar to the contour of the insulator, as shown. The upper insulating member 2 may be provided with the usual petticoat 11 to function as a rain shed.

20 The member 6 is a hollow body, also of bowl shape, to conform substantially to the dielectric field extending from a position adjacent to the perimeter of the petticoat 11 to the pin 5. This construction protects the surfaces of the members 2, 3 and 4 from rain, snow, sleet and dust. These surfaces are in the dielectric field at a position where it is comparatively strong and, therefore, constitute the main insulating surfaces of the insulator. The outer surface of the member 6, being in the dielectric field at a position 25 where the latter is comparatively weak, is less affected by deposits of dust and other conducting matter. The edge 12 of the petticoat 11 projects beyond the upper edge of the member 6 to protect the latter, and is formed to cause rain to drip free of that member.

As shown in Fig. 2, in which the structure is similar to that shown in Fig. 1, an insulating filler 15 is disposed in the member 6 to maintain the surfaces of the members 2, 3 and 4 absolutely free of moisture and other deposits.

In this form, the portion 13 extends to and over the upper end of the pin 5.

While I have shown and described particular forms of my invention, changes may be effected therein without departing from the spirit and scope thereof, as set forth in the appended claims.

I claim as my invention:

65 1. An insulator comprising a main in-

sulating body structure shaped substantially throughout its length to conform to the electrostatic field thereof and an insulating weather-protective envelope therefor shaped to conform to a weaker portion of said field. 70

2. In an insulator, the combination with an insulating structure having a main body member of substantially bowl shape conforming to a portion of the dielectric field of the insulator, of a hollow insulating member of substantially bowl shape conforming to a different portion of said field, said body member being disposed in said hollow member. 75

3. In an insulator, the combination with an insulating structure having a petticoat portion and a main body portion thereunder conforming to the dielectric field of the insulator and having a bottom opening, of a member having a tubular portion disposed in, and depending from, said opening and a portion conforming to said field projecting from the lower end of said tubular portion, in spaced relation to said body portion, to a position under said petticoat portion, adjacent to the perimeter thereof. 80

4. An insulator of the pin-type comprising a main body structure having a portion of substantially bowl shape the sides of which diverge laterally from the longitudinal axis, 85 and longitudinally away from the base, of the pin and a hollow insulating member, of similar shape, constituting a substantially completely enclosing envelope for the sides and one end thereof. 90

5. An insulator for disposition between two zones of different potential in a dielectric field of any predetermined form comprising a member of insulating material having a portion shaped substantially throughout its length to conform to the normal electrostatic field between said zones, and a similar member enclosing the same in spaced relation thereto. 105

6. An insulator for disposition between two zones of different potential in a dielectric field of any predetermined form comprising a main body member of insulating material having its outer surface shaped substantially throughout its length to conform to the normal electrostatic field between said zones, a similar member enclosing the same in spaced relation thereto, to have its field-conforming surfaces in a weaker portion of the field, and a body of insulating material disposed between said members. 110

7. An insulator for disposition between two zones of different potential in a dielectric field of any predetermined form comprising a main body structure of insulating material having its outer surfaces shaped substantially throughout its length to conform to the normal electrostatic field between said zones and a portion shaped to 120

conform substantially to an equipotential surface in said field, and a hollow insulating cover member having field-conforming outer surfaces and inclosing said outer surfaces of the main body structure in spaced relation thereto.

8. An insulator structure comprising a main body portion constructed substantially throughout its length to conform to

the dielectric field in which it is disposed 10 and a member formed in accordance with a weaker portion of said field and surrounding said body portion.

In testimony whereof, I have hereunto subscribed my name this 30th day of December 1920.

FREDERICK H. MILLER.
